UNITED STATES PATENT OFFICE.

HOWARD I. WOOD, OF SCHENECTADY, NEW YORK, ASSIGNOR TO GENERAL ELECTRIC COMPANY, A CORPORATION OF NEW YORK.

VAPOR ELECTRIC LAMP.

1,006,421.

Specification of Letters Patent. Patented Oct. 17, 1911.

Original application filed February 14, 1903, Serial No. 143,329. Divided and this application filed January 23, 1904. Serial No. 190,293.

To all whom it may concern:

Be it known that I, HOWARD I. WOOD, a citizen of the United States, residing at Schenectady, county of Schenectady, State 5 of New York, have invented certain new and useful Improvements in Vapor Electric Lamps, (division of my pending application, Serial No. 143,329, filed February 14, 1903,) of which the following is a specifica- 10

tion. My invention relates to that type of electric lamp in which electricity passes through a vapor contained within an exhausted envelop, and comprises a certain method of 15 starting a lamp of the character mentioned, the novel features of which I have pointed out with particularity in the claims appended hereto.

For a detailed description of my invention, reference is to be had to the following specification taken in connection with the accompanying drawings in which—

Figures 1, 2 and 3 represent by way of illustration some of the various forms which 25 my invention may assume in practice.

As shown in Fig. 1 the envelop of the lamp is a straight glass tube 1, of suitable length, though it is to be understood that the size, shape, length, or other dimensions of 30 the envelop may be widely varied without departing from my invention. At the bottom of the tube is contained a body of mercury 2 forming one of the electrodes with which connection is made by the lead- 35 ing-in conductor 3. The upper terminal of the lamp consists of a cylindrical stick of artificial graphite 4 or if desired this may be replaced by a cylindrical shell of steel or other suitable material, or indeed both elec- 40 trodes may be of mercury or other suitable vaporizable substance. This electrode 4 is supported by a wire 5 of some length, the upper end of which serves as a leading-in conductor, passing through the walls of the 45 tube as indicated at 6, the outer end forming the lamp terminal 7. The conductor 5 is surrounded by a glass tube 8 depending from the upper wall of the glass envelop 1 and extending down to the electrode 4. 50 this tube 8 prevents the electric discharge within the envelop 1 from extending above the electrode 4, and also serves as a mechanical means for preventing lateral dis-

placement of the electrode. Electrically connected to the electrode 4 and extending 55 down therefrom is a filament 9 of carbon or other suitable material, which passes very loosely through a guide or supporting ring or loop 10. The lower end of this filament 9 dips lightly into the surface of the mercury electrode 2, thereby making what may be termed a "poor contact," or a contact possessing high "transition resistance." When now, the lamp, after having been very 60 highly exhausted, is connected with a source of electric current, current flows through the lamp by the circuit afforded by the electrodes 2 and 4 which are electrically connected by the filament 9. The contact between the lower end of the filament and the 65 mercury 2 however is such that the current, in passing between the filament and the mercury, flows through a comparatively small volume of mercury. By reason of this 70 flow of current ionized mercury vapor is 75 produced, the effect of which is to cause an electric arc or discharge to flash into existence between the main electrodes 2 and 4, completely filling the tube. The first incipient arc or discharge takes place between 80 the mercury and the lower end of the filament 9, and extends instantly upward along the filament until it reaches the electrode 4, the action however being too rapid for the eye to follow. The arc or electric discharge 85 which then fills the tube affords a path for the current, of much better conductivity than that presented by the filament 9, so that current practically ceases to flow in the filament, as evidenced by the fact that the 90 filament remains black. It is possible that minute arcs are generated between the mercury 2 and the portion of the filament 9 engaged thereby, though according to my present understanding of the action it seems 95 more probable that the initial disengagement of ionized vapor is due to heat developed by the current flowing through the relatively high resistance contact between the lower end of the filament and the mer- 100 cury.

Instead of arranging the lamp in the vertical position shown in Fig. 1, it may, if desired, be arranged so as to run in a position slightly inclined from the horizontal as 105 indicated in Fig. 2 in which the lamp is of

substantially the same construction as shown in Fig. 1 except that the lower-electrode consists of a body of mercury 11 contained in a slight downward extension 12 of the tube 13. The filament 14 is supported by a guide or guides such as 15 so that its free end rests lightly on or projects slightly into the surface of the mercury 11 as indicated at 16. The operation of the lamp is substantially that described in connection with Fig. 1.

In both the arrangements shown in Figs. 1 and 2 the filament makes a sort of yielding engagement with the surface of the mercury 11 so that slight changes in the level of the mercury caused by more or less condensed mercury accumulating in portions of the tube during operation do not interfere with the operative starting relation between the filament and the mercury electrode. Instead of providing a yielding engagement between the filament and the mercury electrode, afforded by the yielding filament, as indicated in Figs. 1 and 2, I may use an arrangement such as shown in Fig. 3 in which the filament is held in a definite central position by means of encircling guides such as 17. The lower end of the filament however is jointed as at 18, the end 19 thus jointed being thus given a certain amount of play to accommodate itself to variations in the level of the mercury electrode 20.

The starting means which I have above described will operate when alternating current is supplied to the lamp, though I find that the operation is much more satisfactory with direct current, since with alternating current a disintegration of the lower end of the filament takes place, thus blackening the walls of the tube, which action does not take place to the slightest extent with direct current.

I am thus enabled to produce a lamp which is started on the voltage and character of current on which it runs, by merely closing the switch.

What I claim as new and desire to secure by Letters Patent of the United States, is,

1. The method of starting a vapor electric device having an exhausted envelop provided with electrodes, one at least of said electrodes being of vaporizable material, which consists in causing the initial flow of current to enter said vaporizable material through a poor or relatively high resistance contact, so as to generate ionized vapor at said contact, thereby causing the main discharge to take place between said electrodes.

2. The method of initiating an electric discharge between electrodes within an exhausted envelop, one at least of which electrodes is of vaporizable material, which consists in first causing current to flow through a localized portion of the surface layer of the vaporizable electrode and by the local ac-

tion of such current flow disengaging ionized vapor which operates to set up said discharge.

3. The method of initiating an electric discharge between electrodes within an exhausted envelop, one at least of which electrodes is of vaporizable material, which consists in initially causing current to flow through the envelop in a normally conducting path, the resistance of which at the surface of one of the electrodes is sufficient to cause the generation of heat, and therefore the disengagement of conducting vapor.

4. The method of starting a vapor electric apparatus having an exhausted envelop provided with electrodes, one at least of said electrodes being of vaporizable material, which consists in passing current through a path including said vaporizable electrode, and concentrating the heating energy of said current on a relatively small volume of said vaporizable material located in a predetermined position so as to disengage vapor and subsequently develop an arc.

5. The method of starting a vapor electric apparatus having an exhausted envelop provided with electrodes, one at least of said electrodes being of vaporizable material, which consists in passing current through a conductor of small cross-section making a light, surface contact with relatively small volume of said vaporizable material, said current being sufficient in quantity to vaporize some of said material and thereby start an arc.

6. The method of starting a vapor electric apparatus having an exhausted envelop provided with electrodes one at least of which is of vaporizable material, which consists in passing current to the vaporizable electrode through a contact having relatively high transition resistance, said current being sufficient in quantity to disengage ionized vapor from said vaporizable electrode at said contact by the local action of said current, thereby rendering said evacuated envelop conductive for an arc from said vaporizable electrode.

7. The method of starting a vapor electric apparatus having an exhausted envelop provided with electrodes, one at least of said electrodes being of vaporizable material, which consists in passing current through a conductor which contacts at one end with only a small quantity of the surface layer of said vaporizable material, said current being sufficient in quantity to effect localized heating near said contacting end and the disengagement of ionized vapor from said vaporizable electrode near the end of said conductor, thereby starting an arc in said exhausted envelop.

8. The method of starting a vapor electric apparatus having an exhausted envelop provided with electrodes, one at least of said

electrodes being of vaporizable material, which consists in passing current to said vaporizable electrode through a conductor of limited cross sectional area, the point of contact having a higher resistance than said conductor, so as to localize the heating action of said current and thereby start said apparatus.

9. The method of starting a vapor electric apparatus having an exhausted envelop provided with electrodes, one at least of said electrodes being of vaporizable material, which consists in passing current through a

conductor contacting with the surface of said vaporizable electrode and by the action 15 of said current at the end only of said conductor initiating an arc in said envelop while said conductor remains stationary with respect to the main body of said vaporizable material.

In witness whereof, I have hereunto set my hand this 20th day of January, 1904.

HOWARD I. WOOD.
